United States Patent Office

Des. 215,712
Patented Oct. 28, 1969

215,712

SEAT OR SIMILAR ARTICLE

John W. Duckett, Tiburon, Paul W. Poehlmann, San Anselmo, and George E. Scott, San Francisco, Calif., assignors to Composite Structures Incorporated, Sausalito, Calif., a corporation of California

Filed Aug. 23, 1968, Ser. No. 13,244

Term of patent 14 years

Int. Cl. D6—01

U.S. Cl. D15—8

FIG. 1

FIG. 2

FIG. 3

FIG. 4

FIGURE 1 is an isometric view of a seat or similar article showing our design;

FIGURE 2 is a front elevational view;

FIGURE 3 is a rear elevational view; and

FIGURE 4 is a side elevational view taken from the left in FIGURE 1.

We claim:

The ornamental design for a seat or similar article, substantially as shown.
